UNITED STATES PATENT OFFICE.

IRVING C. STERNBERG, OF NEW YORK, N. Y., ASSIGNOR TO ARCTIC NU-AIR CORPORATION, OF CHICAGO, ILLINOIS, A CORPORATION OF ILLINOIS.

DESIGN FOR A CASING FOR THE DISCHARGE MOUTH OF BUILDING-VENTILATING SYSTEMS.

Application filed May 27, 1927. Serial No. 22,196. Term of patent 3½ years.

To all whom it may concern:

Be it known that I, IRVING C. STERNBERG, a citizen of the United States, and a resident of New York, county of Bronx, and State of New York, have invented a certain new, original, and ornamental Design for a Casing for the Discharge Mouth of Building-Ventilating Systems, of which the following is a specification, reference being had to the accompanying drawing, forming a part thereof, and wherein—

Fig. 1 is a perspective front elevational

view of a casing for the discharge mouth of a building ventilating system embodying my invention.

Fig. 2 is a transverse horizontal section therethrough as taken on the line 2—2 of Fig. 1.

I claim:

The ornamental design for a casing for the discharge mouth of building ventilating systems substantially as shown.

IRVING C. STERNBERG.
